US00D952258S

(12) **United States Design Patent** (10) Patent No.: **US D952,258 S**
(45) Date of Patent: **** May 17, 2022**

(54) **ARTIFICIAL EYELASH EXTENSION
APPLICATOR**

(71) Applicant: **Lashify, Inc.**, Los Angeles, CA (US)

(72) Inventor: **Sahara Lotti**, Los Angeles, CA (US)

(73) Assignee: **Lashify, Inc.**, North Hollywood, CA (US)

(**) Term: **15 Years**

(21) Appl. No.: **29/723,252**

(22) Filed: **Feb. 5, 2020**

(56)

CLAIM

An ornamental design for an artificial eyelash extension applicator, as shown and described.

DESCRIPTION

FIG. 1 is an illustration of a front perspective view of an artificial eyelash extension applicator;
FIG. 2 is a front elevation view thereof;
FIG. 3 is a rear elevation view thereof;
FIG. 4 is a right-side elevation view thereof;
FIG. 5 is a left-side elevation view thereof;
FIG. 6 is a top view thereof;
FIG. 7 is a bottom view thereof; and,
FIG. 8 is a bottom perspective view thereof.

1 Claim, 5 Drawing Sheets
